UNITED STATES PATENT OFFICE.

WILLIAM H. MURCHISON, OF BLYTHEVILLE, ARKANSAS.

ICE INDICATOR.

Application filed November 11, 1925. Serial No. 68,360.

This invention relates to an improved household contrivance, which may be conveniently referred to as an ice indicator, the same having reference to a new article of manufacture which is adapted to be suspended upon or near a door, window or the like to permit the same to be seen at a distance by an ice man to indicate the quantity of ice desired by the house wife.

10 Briefly, the invention has reference to a structure including three or more plates provided upon opposite sides with numbers indicating the desired quantity of ice. These are disposed in superposed relation and are suspended from a novel hanger which is of a construction to permit either side of any one of the plates to be disposed to view.

15 The novel hanger, as will be later seen, comprises a supporting member embodying an attaching eye, a depending arm, and a horizontally disposed substantially rectangular loop upon which the numbered plates are supported.

20 The structural features and advantages of the invention will become apparent from the following description and drawings.

25 In the accompanying drawing forming a part of this application, and in which like numerals are employed to designate like parts throughout the same:

30 Figure 1 is a perspective view of a contrivance constructed in accordance with the present invention, showing the manner of using the same.

35 Fig. 2 is a plan view of one of the metal plates showing indicating numbers thereon.

40 Referring to the drawings in detail, the reference character 1 designates the improved hanger, and the characters 2, 3 and 4 designate the numbered plates. Each plate is preferably constructed of a substantially weather-proof material and in practice the plate is painted with black enamel or the like on its opposite faces and the indicating number is painted with white so that it will be visible plainly for quite some distance.

45 Each plate is substantially square in configuration and has its corners cut off as indicated at 5. Moreover, at the top corner is an opening which serves as a means for mounting the plates upon the hanger.

50 The hanger is formed of a single length of wire bent upon itself at one end to form an attaching eye 6, bent at its opposite end to form a horizontal loop 7 and having the intermediate portion of the depending arm 8

offset as at 9. The loop is substantially rectangular in form and the portions 10, 11 and 12 come into play in the adjusting of the plate to bring the desired number to view.

55 In practice, the hanger is fastened upon the wall, door or other suitable support in a place where the numbers can be readily seen by the ice man. Under normal conditions, the three plates are arranged in superposed relation and are hanging from the side portion 10 of the loop 7. Both sides of the plates are provided with numbers for convenience so that either side may be brought to view for display.

60 Assuming that the three disks are hanging in the perpendicular position shown, but that they all three are in alinement and suspended upon the same side portion 10 of the loop 7, and that it is desired to swing the top disk 3 over and underneath the disk 4, as indicated by the reference character 2 in Fig. 1, this will be done as follows:

65 Take all three of the plates and swing them up to the substantially horizontal position indicated in dotted lines at 13. Then take the top plate and swing it in a direction from left to right in order to bring the reverse side to view. When this top plate, which may be plate 3, is in the same plane with the other two as indicated in dotted lines at 14, the opposed corners 5 will be in substantial abutting relation. Now by removing the two plates on the left slightly 70 forward on the portion 10, the plate on the right may be dropped down behind the two plates so that it will be in back of them as indicated in Fig. 1 in full lines. If the number 12½ is in back at the time the plates 75 are so adjusted, this will bring the number 50, appearing on the second plate, to view.

80 As shown in Fig. 2, the plate 3 has the number 12½ on the front face, number 25 on the rear side. Obviously, it is very easy 100 to turn this plate over to bring the number 25 to view.

85 From the foregoing description and drawings it is thought evident that I have evolved and produced a simple and inexpensive contrivance for permanent use which will permit almost any quantity of ice to be ordered. It may be conveniently used either on the outside or on the inside and will withstand comparatively rough use.

90 It is believed that by consideration of the description with the drawings, a clear un-

derstanding of the invention may be obtained. Therefore, a more lengthy description is thought unnecessary.

Minor changes coming within the field of 5 invention claimed may be resorted to if desired.

Having thus described my invention, what I claim as new is:—

- 10 1. In an ice indicating device of the class described, a hanger comprising an attaching arm having a horizontally disposed loop, and a plurality of substantially rectangular plates of substantially indestructible material having their corners cut out dia-
- 15 ginally, said plates being provided with indicating numbers and being provided at one corner with an opening slidably

mounted upon said loop to permit said plates to be disposed in superposed relation and to be inverted.

20

2. In an ice indicating device of the class described, a hanger comprising an attaching arm adapted to be connected with a stationary support and having a horizontally disposed loop, and a plurality of 25 plates provided with indicating numbers and being formed with openings slidably mounted upon the portions of said loop to permit said plates to be disposed in superposed relation and to be inverted to display 30 the desired indicating numbers.

In testimony whereof I affix my signature.

WILLIAM H. MURCHISON.
